GARMENT HANGER

James Woods, Buffalo, N. Y., assignor to James R. MacDonald and Company, Buffalo, N. Y., a corporation of New York

Application August 18, 1937, Serial No. 159,769

2 Claims. (Cl. 223—96)

This invention relates to improvements in garment hangers of the type in which a pair of clamping members or jaws are hinged together and held in clamping position by a lever.

5 One of the objects of this invention is to provide a device of this character with a lever which is curved and twisted about itself in a manner to form a hook of novel construction for suspension on a rod or other support.

10 Other objects of the invention will be apparent from a study of the following description and drawing in which:—

Figure 1 is a perspective view of the invention.

Figure 2 is a fragmentary view of one of the 15 clamping rod members which is engaged by the hook portion.

The jaws or clamping members 1 are made preferably of strips of wood lined with felt pads 2 on their inner surfaces. The clamping members 1 are connected by a hinge constructed of small rods, the axis of the hinge being shown at 3. There are two such rods 4 and 5 having their ends received in openings formed in the clamping members 1. The rod 5 is bent around the rod 4 so as to form a bearing for the rod 4 when the clamping members 1 are moved into open position. The rods 4 and 5 have formed therein U-shaped portions 6 and 7 intermediate their ends, the U-shaped portion 7 providing an axis for a lever 8.

The lever 8 is formed of a rod bent intermediate its ends to form the curved portions 11 and 12, constituting a hook 10. Extending from the curved elements 11 and 12 are shank portions 13 and 14. The shank 13 is formed into a coil 15 around the shank 14 in such a manner as to securely hold the shank portions together. Extending from the coil 15 of the shank portion 13 and the shank 14 is a pair of angular leg portions 16. The lower portions 17 of the angular leg portions 16 terminate in eyes 18 journaled about the U-shaped portion 7. The U-shaped portion 6 is provided with notches 19 for receiving the angles 20 of the leg portions of the lever 8.

45 When the device is to be used the lever 8 is swung downwardly disengaging the legs 16 from the U-shaped member 6 thus allowing the clamping members 1 to be spread apart for the inser-

tion of trousers or other garments to be clamped between said clamping members 1. When the lever 8 is swung upwardly the legs 16 engage the U-shaped portion 6 thereby bringing the clamping members 1 into clamping position. Lever 8 comes to rest when the angles 20 engage in the notches 19 in the U-shaped portion 6. The hook 10 of the lever 8 is used for hanging the device from a suitable support.

I claim:

1. In a hanger of the type comprising a pair of hingedly connected rods including substantially U-shaped intermediate portions and coacting jaws on said rods, a lever for releasably securing the jaws in closed position, said lever comprising a single length of wire folded upon itself at an intermediate point and formed to provide a hook, a pair of parallel shanks extending from said hook, a coil on one of said shanks encircling the other shank, and a pair of diverging legs extending downwardly from said coil and said other shank, and lateral parallel extensions on said legs terminating in eyes journaled on one of said U-shaped portions, said legs being slidably engageable with the other of said U-shaped portions for closing and holding the jaws in closed position.

2. In a hanger of the type comprising a pair of hingedly connected rods including substantially U-shaped intermediate portions and coacting jaws on said rods, a lever for releasably securing the jaws in closed position, said lever comprising a single length of wire folded upon itself at an intermediate point and formed to provide a hook, a pair of parallel shanks extending from said hook, a coil on one of said shanks encircling the other shank, and a pair of diverging legs extending downwardly from said coil and said other shank, lateral parallel extensions on said legs terminating in eyes journaled on one of said U-shaped portions, said legs being slidably engageable with the other of said U-shaped portions for closing and holding the jaws in closed position.

JAMES WOODS.
